UNITED STATES PATENT OFFICE.

MARTHA A. YATES AND ODAVILLE YATES, OF PORTLAND, OREGON.

RACK.

1,378,161.

Specification of Letters Patent. Patented May 17, 1921.

Application filed August 20, 1919. Serial No. 318,764.

To all whom it may concern:

Be it known that we, MARTHA A. YATES and ODAVILLE YATES, citizens of the United States, residing at Portland, in the county 5 of Multnomah and State of Oregon, have invented certain new and useful Improvements in Racks; and we do hereby declare the following to be a full, clear, and exact description of the invention, such as will 10 enable others skilled in the art to which it appertains to make and use the same.

This invention relates to racks, and more particularly to a rack specially adapted for holding toilet articles.

15 One of the main objects of the invention is to provide a rack of simple construction and operation which is adapted to support a plurality of towels and similar articles, the towel holding means being also adapted

20 to support toothbrushes or like articles.

A further object is to provide a rack of the character stated which may be produced at comparatively small cost and may be readily applied.

25 Further objects will appear from the detailed description.

In the drawings:

Figure 1 is a front view of a rack constructed in accordance with the invention.

30 Fig. 2 is a top plan view.

Fig. 3 is a section taken substantially on line 3—3 of Fig. 1.

The rack includes a main supporting bar 1 of substantial U-shape the ends of the 35 arms of which are secured by plates 2 to a suitable base board 3. This bar is provided with a plurality of tubular towel holding members 4 secured thereto in vertical position, each of these members being formed 40 of sheet metal of suitable gage and having its upper end portion turned over at right

angles to provide a substantially horizontally disposed head 5 which is provided in each end with a keyhole slot 6 for reception of a toothbrush or similar article. This 45 head is connected to the upper end of tube 4 by a neck 7 which merges into the upper end portion of the tube, this tube being split as at 8 to form two resilient securing arms the upper end portion of which is 50 turned outwardly as at 9 to facilitate insertion of a towel or similar article into the tube. The tube is preferably, though not necessarily, of substantial ovoidal shape in 55 cross section so as to produce the desired resiliency of the gripping arms, the towel or other similar article to be secured being readily inserted into the tube from either end thereof and removed by being drawn from the tube at either end. 60

What we claim is:

As a new article of manufacture, a rack comprising a transverse bar, a plurality of spaced leaves formed on said bar and extended vertically with their side edges rolled 65 inwardly toward one another and their flared upper ends turned back in a horizontal plane and provided with notches in their opposed edges, the notches being adapted to accommodate handles of toothbrushes, the 70 upstanding portions of the leaves forming tubes to receive towels to be suspended in spaced relation with respect to the stationary support. 75

In testimony whereof we affix our signatures in presence of two witnesses.

MARTHA A. YATES.
ODAVILLE YATES.

Witnesses:
